APPARATUS FOR LUBRICATING THE JOURNAL OF A RAILWAY VEHICLE

Gilbert Brereton, 55 Russell Ave., Ottawa,
Ontario, Canada

Filed Aug. 15, 1960, Ser. No. 49,619
6 Claims. (Cl. 308—88)

The invention relates to apparatus for lubricating the journals of railway cars.

According to the most commonly used methods lubrication of the journal within the journal box is accomplished by packing tightly around the journal a quantity of absorbent material, such as bunched cotton threads, commonly known as waste, soaked in oil. As by this method constant frictional contact must be maintained between the journal and the surrounding waste great care must be taken to keep the waste supplied with oil, not only from the standpoint of efficient lubrication but from the point of danger of fire which would almost certainly result from frictional engagement between the rapidly rotating journal and waste which had become dry. Ignition of waste usually results in burnt-out bearings and other costly damage, besides frequently necessitating stops on the right-of-way, with resultant danger of accident.

According to the present invention the oiling mediums are in the form of wick-like elements projecting upwardly from within an oil reservoir within the journal box and so supported that although in contrast contact with the journal at opposite sides thereof, they are not under pressure, and further are mounted for limited rocking movement relative to the journal, so that danger of fire through frictional contact between the rotating journal and the oiling mediums is entirely eliminated, even though through lack of attention the wick-like oil transferring medium should become dry temporarily through depletion of oil in the reservoir.

The main object of the invention is to provide simple and dependable lubrication apparatus which will insure proper lubrication of the journal for the maximum length of time with a given quantity of lubricant.

Another important object of the invention is to provide a lubricant feed assembly constructed entirely of flexible material, such as rubber and fabric and of such dimensions that the entire assembly can be readily passed through the conventional door of the journal box for insertion and removal.

And generally the objects of the invention are to provide efficient lubricating apparatus of simple and durable construction, which will require no attention after installation and which will be inexpensive to produce.

An important feature of the invention resides in the oil transferring mediums, which may consist of hair-like fibres, preferably woven into wick-like form, having the ability to absorb oil and to raise it through capillary attraction from an oil reservoir in the bottom of the journal box into contact with the journal.

Another important feature of the invention resides in the carrier for the oil transferring mediums, such carrier comprising a cradle structure of substantially U-shaped cross section elongated lengthwise of the journal box beneath the journal and mounted to rock transversely of the longitudinal axis of the journal, the said cradle having upright sides extending above the horizontal centre of the journal and being spaced apart, somewhat greater than the diameter of the journal, said sides being adapted to support the oil transferring wicks folded thereover at their longitudinal centres so that the portions of the wicks at opposite sides of their folds will depend downwardly over the inner and outer surfaces of the respective sides of the cradle. The bottom of the cradle

2

has a lengthwise extending slot in its transverse centre to receive the inner folds of the wicks, which extend downwards at an inward incline from the top edges of the cradle sides in spaced relation to the inner surfaces of said sides and pass through said slot and are joined beneath the bottom of the cradle body to the outer folds which extend down the outer surfaces of the cradle sides, the folds of the wicks being of sufficient length to provide generous portions below the cradle adapted to lie immersed in oil in the reservoir formed in the bottom of the journal box. The cradle has its bottom rounded transversely, or has rockers attached thereto, so as to permit limited rocking movement thereof transversely of the journal through vibratory motion of the car and thus prevent any danger of pressure on the wicks which might cause same to be unyieldingly held to contact with the journal.

Still another important feature of the invention resides in the manner of removably attaching the oil transferring mediums to the cradle whereby they may be quickly attached or detached.

With the above and other objects in view the invention consists in the novel features of construction, arrangements and combinations of parts set out in the present specification and more particularly pointed out in the claims for novelty following.

In describing the invention reference will be made to the accompanying drawings, in which:

FIGURE 1 is a longitudinal section through a journal box equipped with my improved journal lubricating apparatus, the associated portion of the journal being shown in full.

FIGURE 2 is a vertical section on the line 2—2 of FIGURE 1, showing the rockable cradle which carries the journal lubricating wicks tilted in one direction.

FIGURE 3 is a view similar to FIGURE 2, showing the cradle tilted in the direction opposite to that shown in FIGURE 2.

FIGURE 4 is a top perspective view of the rockable cradle and the oil transferring mediums carried thereby.

FIGURE 5 is a vertical section through one side of a cradle having two lubricating wicks over its inner wall surface.

Like numerals of reference indicate corresponding parts in the various figures.

Referring to the drawings, 1 denotes a journal box such as is commonly used to receive through one end wall thereof, indicated at 2, the one end of axle 3, which latter has that portion 4 of its length within the journal box reduced in diameter and provided with a head 5 at its extreme outer end.

The journal box is of conventional shape, comprising a flat top 6, side walls 7 extending downwards in parallel relation to one another for the greater part of the depth of the box and then reducing, as at 8, to a medial relatively narrow bottom 9, so that there is provided a reservoir 10 which extends lengthwise the full extent of the box.

60 A metal block 11 of a width slightly greater than the diameter of the journal 4 and in length being somewhat shorter than the said journal, extends lengthwise of the journal in spaced relation thereto and has mounted in a suitable recess in its lower face a bearing member 12 of babbitt metal, which is curved transversely as at 13, throughout its length to conform to the cross-sectional shape of the journal 4 with which it lies in contact. The block 12 is secured within the journal box with its flat top parallel with the inner face of the top wall of the box by means of lateral extensions 14 of the block 11 which lie between the top of the box and flanges 15 which project inwards from the walls 7 of the box. The extensions 14

are slightly less in depth than the space between the flanges 15 and the top 6 to permit of limited up and down movement of the block 11 due to vibration. The total width of the block 11 including the extensions 14 is slightly less than the interior width of the box, as is shown in FIGURE 2. The end wall 16 or the journal box opposed to that through which the journal extends is projected outwardly and downwardly from the top 6 for the greater part of its depth to provide an inclined part which recedes from a point below the vertical centre of the journal box to the bottom, as shown at 17. This inclined wall is provided with a door 18 hinged at its top, as at 19, to swing upwardly to provide access to the interior of the box. Ribs 20 extend along the sides of the journal box in opposition to one another at points somewhat above the horizontal centre of the journal.

The journal box and journal structure thus far described is conventional in character and applicant does not claim novelty for such structure, his invention residing in means in combination with such described means to provide lubricating contact with the journal within the conventional journal box.

A cradle-like carrier 21 provides the means for supporting wick-like lubricating elements 22 and 23 with their ends immersed in lubricating material in a reservoir 10 formed in the bottom of the journal box, and portions of their lengths in contact with the journal at opposite sides thereof. This carrier, hereinafter referred to as the cradle, consists of a moulded rubber device of substantially U-shaped cross section, which extends almost the entire length of the part 4 of the journal and has its bottom rounded transversely, as at 24.

The cradle has outstanding ribs 25 at its ends, extending around its bottom 24 and its sides 26 and 27 and adapted to lie on the bottom of the reservoir and so hold the bottom spaced above the bottom of the reservoir, and also provides rockers for the cradle.

The closed bottom of the U-shaped cradle is of considerably greater vertical thickness than the horizontal thickness of the sides and has in its transverse centre a vertical slot 28 extending throughout the greater part of that portion thereof which lies between the ribs 25. The sides of the cradle are spaced apart a distance somewhat greater than the diameter of the journal and extend upwards in slightly inward curves to points somewhat above the centre of the journal and short of the internal ribs 20 of the journal box.

As means to limit the lateral rocking movement and, further, to provide means for holding the wicks 22 and 23 in position, as will be explained more fully herein-after, rubber studs 29 and 30, which are preferably cast integral with the cradle sides, are arranged to project laterally from the outer surfaces of the cradle sides near the top edges of said sides, said studs being in the rocking movement of the cradle adapted to impinge the side walls of the journal box alternately and being of such length as to limit the tilt of the cradle to a slight degree in respect to the journal.

As means to transfer oil from the reservoir 10 of the journal box into contact with the journal at opposite sides of the latter I employ two wick-like members 22 and 23, hereinbefore mentioned. Each of the wicks is folded in substantially its longitudinal centre over the top end of a side of the cradle to provide inner portions 28a and outer portions 28b and the end of each portion 28a within the cradle is passed through the slot 28 in the bottom of the cradle and drawn sufficiently tight that the portion below the top end of the cradle side and the slot 28 will normally lie spaced from the cradle side and in yielding contact with the journal from substantially its lowest point to substantially its outermost circumferential point. The portion 28b of each wick is drawn downwardly over the outer surface of the cradle side over which it lies and is secured to the inner fold of the same wick by means of stitching 31, or by any other suitable fastening means,

and the end portions 32 of the wicks beyond their connected points 31 are preferably turned laterally to lie immersed in the lubricant contained in the reservoir 10.

The portions of the wicks which extend over the outer surfaces of the cradle sides are provided with apertures 33 suitably located to receive the studs 29 and 30 to hold the said wicks against displacement.

Straps 35 extended through suitable slots 36 in the sides of the cradle near at least one end thereof and having their ends detachably secured together by some suitable type of fasteners, indicated at 37, provide means for carrying the cradle and for facilitating the withdrawal of same from the journal box.

In the use of this invention the wick members 22 and 23 are first folded over the top edges of the sides of the cradle and the inner folds threaded through the slot 28 in the bottom of the cradle, after which the outer folds are drawn downwardly and fastened to the inner folds at the corresponding sides. The assembly is then inserted through the door of the journal box and placed in position on the floor of the box with the end portions 32 of the wicks immersed in the lubricant which has previously been placed in the reservoir. In this position the inner folds of the wicks will extend around and lie in constant engagement with the lower half of the journal and as the wicks are in a continual state of saturation due to oil being drawn by capillary attraction from the reservoir the oiled surfaces of said wicks will be brushed by the rotating journal and therefore kept in a properly lubricated condition.

Because the ribs 25 which provide the supports for the cradle are rounded transversely of the cradle the vibration caused by the motion of the car will cause the cradle to rock gently, thereby continually varying the degree of friction between the wicks and the journal, thus tending to prolong the life of the wicks and making for economy in oil consumption.

In the event that through excessive vibration of the car the cradle should have a tendency to creep upwardly, at one side of the journal box the corresponding cradle side will impinge the rib 20 and so be prevented from further upward movement.

In FIGURE 5 a modified structure is shown in which two wicks are used at each side of the journal to raise oil from the reservoir 10, there being a wick 39 positioned between each of the inner folds of the wicks 22 and 23 and the corresponding sides of the cradle. The wicks 39 lie behind the wicks 22 and 23 and have suitable button-hole like apertures 40 near their one ends which receive the studs 29 and 30 and said wicks 39 extend over the top edges of the cradle sides parallel with the inner folds of the wicks and through the slot 28, where they are connected by suitable stitching to the inner and outer folds of the wicks at the corresponding sides, and they have end parts extending beyond said connections to lie in the oil in the reservoir 10.

The present invention provides simple, efficient and economical means for lubricating the journals of railway vehicles.

While I have shown and described herein the present preferred forms of construction and arrangements of parts for carrying out my said invention, these are capable of variation and modification, I, therefore, do not wish to be limited to the precise details of construction and arrangement of parts set out herein but desire to avail myself of such variations and modifications as come within the scope of the appended claims.

What I claim as my invention is:

1. Lubricating means for the journal of a railway vehicle, said means including a journal box having an oil reservoir below the journal and oil therewithin, a cradle supported within said journal box below said journal and adapted for rocking movement transversely of the journal box, said cradle having an exteriorly rounded bottom and

sides extending upwardly therefrom, the interior surface of said bottom and sides following generally the curvature of said journal but on a greater radius, said cradle having a slot through its bottom extending lengthwise thereof beneath the journal, wick-like sheets of absorbent material folded over the top edges of said cradle sides, respectively, and depending downwardly thereover and having their ends immersed in the oil in said reservoir, the portions of said wick-like elements which extend downwards within said cradle passing through said slot in the bottom of the cradle, fastening means securing together the inner and outer folds of the respective sheets of absorbent material around the corresponding cradle sides whereby the folds thereof which extend downwards within the cradle will be held out of contact with the interior surfaces of the cradle sides and will provide yieldable oiling mediums in continuous contact with the bottom and lower side of the journal, and means to limit the rocking movement of said cradle.

2. Lubricating means for the journal of a railway vehicle having a journal box receiving a journal through one of its ends and having a door in its other end, said journal box having an oil reservoir extending lengthwise thereof beneath the journal and containing oil therein, a cradle comprising a flexible, resilient member deformable for entry through said door, said cradle comprising a body of substantially U-shaped cross section elongated lengthwise of the journal box beneath the journal and having a rounded bottom and sides rising to at least the vertical centre of the journal, the interior transverse curvature of said cradle following substantially the contour of said journal but on a greater radius, said cradle having in the transverse centre of its bottom a slot elongated lengthwise of the bottom, said cradle further having lateral flanges near its ends constituting rockers adapted to seat on the bottom of said reservoir, studs extending laterally from the outer surfaces of the cradle sides in spaced relation to each other lengthwise of said sides, wick-like absorbent elements folded over the top edges of said cradle sides and depending downwards at opposite sides of said cradle sides and having their ends immersed in the oil in said reservoir for transferring oil by capillary attraction to the portions of said elements within said cradle, said portions of said wick-like elements depending downwardly within the cradle inclining from the top edges of the cradle sides to said slot and passing therethrough, and means for holding the said inclined portions of said wick-

like elements free of contact with the inner surfaces of the cradle sides.

3. Lubricating means for the journal of a railway vehicle, according to claim 2, characterized in that said wick-like elements have apertures therethrough adapted to receive said studs extending from the outer surfaces of the cradle sides to locate said elements in respect to said cradle sides.

4. Lubricating means for the journal of a railway vehicle, according to claim 1, characterized by horizontally aligned ribs extending along the inner surfaces of the sides of the journal box to limit the upward tilting movement of said cradle.

5. Lubricating means for the journal of a railway vehicle, according to claim 1, characterized by looped straps extending through apertures in the sides of the cradle to provide means for facilitating withdrawal of the cradle from the journal box.

6. Lubricating means for the journal of a railway vehicle, said means including a journal box having an oil reservoir below the journal and oil therewithin, a cradle supported within said journal box below said journal and adapted for rocking movement transversely of the journal box, said cradle having an exteriorly rounded bottom and sides extending upwardly therefrom, studs extending laterally from the outer surfaces of said cradle sides, the inner surfaces of said bottom and sides following generally the curvature of said journal but on a greater radius, said cradle having a slot through its bottom extending lengthwise thereof beneath and in substantial vertical alignment with the transverse centre of the journal, wick-like sheets of absorbent material folded over the top edges of said cradle sides, respectively, the portions of said wick-like sheets at the outer sides of said cradle sides being removably secured on said studs, the portions of said wick-like sheets within said cradle extending downwardly in converging relation to each other at opposite sides of and in continuous yielding contact with said journal and extending through said slot and having their lower ends immersed in the oil in said reservoir, and means to limit the rocking movement of said cradle.
